STOKER MECHANISM

William Thompson Hanna, Cincinnati, Ohio

Application May 23, 1935, Serial No. 22,967

2 Claims. (Cl. 110—105.5)

This invention relates to stoker construction and more particularly to a stoker construction for use on a locomotive.

One of the objects of this invention is to provide a stoker construction which is simple and inexpensive in construction and sturdy and durable under conditions of rigorous use. Another object is to provide a standard construction of the above nature which assures a uniform delivery of fuel to a boiler. Another object is to provide a standard construction of the above nature which may be used on a variety of locomotives. Another object is to provide a standard construction of the above nature which can be readily installed on a locomotive boiler backhead with a minimum of fittings and handling of heavy parts while so doing. Another object is to provide a construction of the above nature which may be readily removed from one locomotive and installed on another without necessitating extensive replacement of parts. Another object is to provide an adapter unit which is relatively inexpensive and light in weight and by the use of which a standardized stoker can be installed on locomotives of different types. Other objects will be in part apparent and in part pointed out hereinafter.

The invention accordingly consists in the features of construction, combinations of elements, and arrangements of parts as will be exemplified in the structure to be hereinafter described and the scope of the application of which will be indicated in the following claims.

In the accompany drawing in which is shown one of the various possible embodiments of this invention,

Figure 1 is a vertical section of a backhead of a fire box on which is mounted the delivery end of a stoker and adapter embodying the invention;

Figure 2 is a front elevation of an adapter unit embodying the invention; and

Figure 3 is a vertical section taken along the line 3—3 of Figure 2.

Similar reference characters refer to similar parts throughout the several views of the drawing.

An overfeed stoker for locomotives usually comprises a transfer conduit for moving fuel forwardly from a tender to a point below and to the rear of the fire door of the fire box of the locomotive. Joined to this transfer conduit is a large housing (commonly called a fuel supply housing) mounted on the boiler back of the boiler, the housing surrounding the firing opening and sup-

porting various devices used for effecting distribution of the fuel over the fire bed. This housing is generally large, heavy and expensive to manufacture and handle, and so by its inherent size causes some difficulties in properly mounting it on the backhead of the locomotive.

The simplest and probably the most economical means employed for moving the fuel through the stoker are screw conveyers, for which use the stoker parts must be carefully designed to avoid obstructions to the flow of fuel which is relatively easily stopped. For this reason, for example, the angle which the fuel takes in flowing from the transfer conduit to the housing must come within well-defined limits. The angle (with respect to the vertical) of the path that the fuel takes through the housing is carefully worked out for maximum efficiency. Each housing is preferably designed to take care of these factors to provide for the most efficient flow of the fuel through it and is designed so that its parts are located in predetermined positions with respect to the horizontal and vertical when in place on a locomotive. Since these housings are so large and expensive and are usually made from castings, it is of course desirable to standardize them in so far as possible. But in the way of such standardization is the fact that there is no standard angle of the backheads of locomotives with respect to the vertical and such angle may vary over fifteen degrees among different locomotives. Consequently, if a standardized housing were designed to be mounted on a boiler backhead sloping fifteen degrees from the vertical it would not be correctly mounted on a vertical boiler backhead or one sloping five or ten degrees from the vertical and it is an object of the present invention to solve this problem so that a standardized fuel supply housing may be adapted to different backheads regardless of their slope from the vertical, if any.

Referring now to Figure 1, a fire box generally indicated at 10 has a backhead 11 having the usual fire opening 12. Backhead 11 is inclined with respect to the vertical and has mounted thereon a fuel supply housing generally indicated at 13 which is a part of a mechanical stoking mechanism, such, for example, as is described in my Patent No. 2,044,001. Fuel forced upwardly through an elevating conduit 14 flows into housing 13 whence it moves over a distributing unit generally indicated at 15 by which it is distributed over the fire bed in fire box 10.

The back side of the fuel supply housing has an opening 16 which is partially covered by a

suitable fire door mounting 17 secured to the housing and through which the operation of the stocker may be examined or the fire hand fired. The lower portion of housing 13 includes a flanged portion 13b which is secured to a complementary flanged portion 14b of elevating conduit 14 by bolts 40 or the like. Elevating conduit 14 has a universal connection (not shown) by which it is connected with the fuel feeding mechanism (not shown) carried by the locomotive and tender. This universal joint allows for relative movement between the locomotive and tender such as would occur on curves, for example. It is preferable, however, that elevating conduit 14 be maintained in a predetermined position; that is, its axis should never exceed a desirable angle of inclination with respect to the vertical. Accordingly, fuel supply housing 13 is definitely positioned at a predetermined desirable angle of inclination with respect to the vertical. Accordingly, such a housing is hereinafter characterized as "standardized" or "standard."

The fuel supply housing includes a wall portion 13a which extends upwardly from flanged portion 13b and terminates in a fuel delivery ledge or shelf 18 which is disposed in the forward opening of the housing and is substantially contiguous to fire opening 12. The surface of this ledge or shelf preferably lies in a horizontal plane when the fuel supply housing is correctly positioned as pointed out above.

Fuel distributing unit 15 includes brackets or portions 31 which are mounted on steam pipes 31a through which steam flows into the fuel distributing unit. Steam pipes 31a extend through the opposite sides of an adapter plate generally indicated at 19 as by way of holes 31b (Figures 2 and 3). A blast chamber 32 extends downwardly from brackets 31 and is provided with a number of steam jets 33 and 34 through which steam flows to distribute fuel delivered thereto from shelf 18, as is more specifically described in my copending application, Serial No. 722,833, filed April 28, 1934. When housing 13 and adapter 19 are in position, steam jets 33, which are disposed in a fan-like arrangement, preferably lie in a plane substantially parallel to the surface of delivery shelf 18. Thus fuel flowing over shelf 18 falls into the path of steam ejected by jets 33 and 34 and is distributed over the fire bed in fire box 10 at a predetermined uniform rate and manner.

Supply housing 13 (Figure 1) is preferably of a standard construction and is provided with a suitable mounting face formed by a portion 28 preferably integral with and extending from wall 13a of the housing and by flange portion 29. Portion 28 has a ledge 28a, the surface of which lies in the plane of the mounting face.

As has been pointed out above, the angle of inclination of backhead 11 very often varies considerably among different locomotives. Accordingly, to maintain the correct position of a "standardized" fuel supply housing 13 with respect to the vertical when mounted on a fire backhead of any or no inclination, I have provided a series of adapter plates 19 of different sizes. With reference to Figures 2 and 3, each adapter 19 is preferably a casting comprising a frame portion 20 (Figure 2) which embraces fire opening 12 (Figure 1). Frame portion 20 (Figure 3) has a suitable number of holes 20a formed therein to receive studs 21 (Figure 1) by which adapter 19 may be secured to backhead 11. The adapter (Figure 3) is also provided

with tapering wall portions 22 (Figures 2 and 3) and a top portion 23. Extending downwardly from top portion 23 is a flange portion 24 (Figure 3) and extending toward one another from the upper portions of walls 22 are mounting faces 25 (Figure 2). A wall portion 26 (Figure 3) extends across the lower portion of the opening defined by frame 20 and preferably has formed therewith an outwardly extending flange 27. The rearward edge 22a (Figure 3) of walls 22, 10 the surfaces of mounting faces 25 and the surface of flange 24 all preferably lie in the same plane and form a suitable mounting face which is complementary to the mounting face of supply housing 13. 15

Assuming that the angle between the rear surface of backhead 11 and the mounting face of the fuel supply housing has been determined, to join the housing and backhead it is only necessary to choose an adapter of the size sufficient to fill this angle and so to provide a mounting whereby the fuel supply housing is maintained in its proper angular position both with respect to the backhead of the boiler and with respect to the vertical. Suitable studs 30 25 maintain the adapter and the fuel supply housing in assembled relation.

It may now be seen that adapter 19 is substantially wedge shaped and, compared to the fuel supply housing, is a relatively small and 30 light part which may be made in a multitude of sizes without incurring any considerable expense. Depending upon the dimensions and proportions of the various portions of the adapter, such as walls 22 and flange 27, a standard fuel supply housing may be adapted to a locomotive backhead of substantially any angularity without effecting a change from the correct operative position of any of the stoker parts, such as the fuel supply housing and elevating conduit 14. 35

In operation, fuel is fed into elevating conduit 14 by the stoker mechanism (not shown) and thence is forced up into housing 13 until it approaches the level of delivery shelf 18. It 45 then overflows shelf 18 at a predetermined and uniform rate and falls into the path of the steam ejected by jets 33 and 34. Thus the fuel is blown into and uniformly distributed over the fire bed in fire box 10. In the event that the 50 stoker mechanism becomes damaged, during operation, the fire may be hand fed through the openings in fire door mounting 17 and housing 13 which are in alignment with firing opening 12. 55

It may now be seen that by providing adapter 19 in a multitude of sizes, a standard fuel housing can be adapted to a backhead of practically any degree of slope, and the desired horizontal position of fuel shelf 18 and the desired vertical position of housing 13 can be maintained. 60

Thus, it will be seen that I have provided a stoker construction in which the above objects in addition to many others are achieved in a thoroughly practical and efficient manner.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense. 65

I claim:

1. In combination with a locomotive fire box having a back wall with a firing opening therein, plate-like stoker supporting means registering 75

5 with said firing opening and having securing flanges abutting the back wall and secured thereto, said means including a rearwardly extending web of greater depth at its top than at its bottom and also housing-supporting flanges 10 extending laterally from said web, the faces of said supporting flanges thus being angularly disposed with respect to the faces of said securing flanges, a stoker fuel discharge housing communicating with said firing opening and having fuel-manipulating instrumentalities therein designed to be positioned at predetermined operating angles with respect to the vertical and horizontal when the stoker is mounted in operative 15 position on the back wall, said housing having laterally projecting flanges at its forward end abutting said supporting flanges, means for securing said forward and supporting flanges together, and said supporting means having a predetermined angularity between its securing flanges and supporting flanges so as to support the fuel discharge housing on the back wall with that angularity between the back wall and forward flanges necessary to support the fuel discharge housing at the desired angle.

20 25 2. In combination with a locomotive fire box having a back wall with a firing opening there-

in, plate-like stoker supporting means registering with said firing opening and having securing flanges abutting the back wall and secured thereto, said means including a rearwardly extending web of greater depth at its top than at its bottom and also housing-supporting flanges 10 extending laterally from said web, the faces of said supporting flanges thus being angularly disposed with respect to the faces of said securing flanges, a fuel discharge housing communicating 15 with said firing opening and having fuel-manipulating instrumentalities therein designed to be positioned at predetermined operating angles with respect to the vertical and horizontal when the stoker is mounted in operative position on the back wall, said housing having laterally projecting flanges at its forward end abutting said supporting flanges, means passing through said flanges for rigidly securing the housing to the supporting means, and said supporting means 20 having a predetermined angularity between its securing flanges and supporting flanges so as to support the fuel discharge housing on the back wall with that angularity between the back wall and forward flanges necessary to support 25 the fuel discharge housing at the desired angle.

WILLIAM THOMPSON HANNA.
